VALVE.

979,811.

Specification of Letters Patent. Patented Dec. 27, 1910.

Application filed April 30, 1909. Serial No. 493,118.

To all whom it may concern:

Be it known that I, AXEL B. WALLEM, a citizen of the United States, residing at Moores, in the county of Delaware and State 5 of Pennsylvania, have invented certain new and useful Improvements in Valves, of which the following is a specification.

This invention is directed to the provision of a valve of an improved construction 10 adapted particularly for use as a relief-valve for a heater, condenser, heating system or the like.

The object of the invention is to provide a valve of this type so constructed that it can 15 be relied on to operate when the conditions under which its operation is desired arise, which permits of readily adjusting the pressure at which the valve will open, which may be conveniently installed and operated, 20 and which, due to the simplicity of its construction, can be manufactured at low cost.

Relief-valves for use in the exhaust of a steam-engine system as heretofore constructed have not been satisfactory, principally for 25 the reason that the movable valve-members frequently stick to their seats and thus prevent the valves from opening even though the pressure at which they should open is reached or exceeded. There may be long 30 intervals between successive operations of such a relief-valve and during this time the movable valve-member may, and often does, become stuck to its seat; and when the conditions of high back-pressure do arrive, it 35 is of great importance that the valve should operate properly to relieve them. Another objectionable characteristic of the relief-valves heretofore used is that vibration of the moving parts is apt to occur, causing a 40 disagreeable rattling noise. My invention is directed to the provision of a valve in which these objectionable features are not present, and one expedient which I employ to this end is the use of a plurality of inde- 45 pendently movable valve-members any one of which may be moved to open an exhaust port and thus relieve the back-pressure; thus, if any one or two of these valve-members stick to their seats, one or more of the 50 others will still be operative to furnish the necessary relief. These valve-members are normally held upon their seats by springs or equivalent weights and devices are provided for regulating the tension exerted by these

springs; this regulating means is so constructed that the tension of all the springs may be equally and simultaneously adjusted and this from any convenient position and without opening the casing of the valve. The spring-adjusting devices are also ar- 55 ranged, in the preferred form of the valve, so that all the movable valve-members may be readily raised from their seats, either simultaneously or successively, in order to 60 guard against the possibility of some of the members sticking to their seats or, if desired, to permit of operating with the exhaust 65 open. These and other features of improvement which are characteristic of the valve of my invention are more fully set forth in 70 the following description referring to the accompanying drawings.

In these drawings, which illustrate valves embodying my invention, Figure 1 is a vertical section of the valve; Fig. 2 is a horizontal section thereof; Fig. 3 is a detail view hereinafter referred to; Fig. 4 is a vertical section of a modified form of valve; Figs. 5 and 6 are elevations of further modifications of the valve; Fig. 7 is a horizontal section of the casing of the valve shown in Fig. 4; and Figs. 8 and 9 are views illustrating further embodiments of 75 the invention.

Referring to these drawings, 1 and 2 illustrate the lower and upper portions, respectively, of the casing of the valve, these being provided with flanges at their adjacent ends having openings therein to receive bolts by which the two portions of the casing are 80 secured together. The lower portion 1 of the shell has a plate or valve-deck 3 formed integral therewith, and this plate has a plurality of openings 4 therethrough. The upper surface of the plate 3 about each of 85 the openings 4 is ground true, so as to form a seat for a movable valve-member 5. Projecting upwardly from the plate 3 are a plurality of posts or standards 6, four being shown in the present instance, and these 90 posts serve as guides for a movable pressure-plate 7 having openings therein through which the posts 6 extend. At the center of the pressure-plate 7 is a threaded opening 95 adapted to receive a threaded shaft 8 the lower end of which is received in a bearing formed in the plate 3 at the center thereof. At its opposite end the shaft 8 may be re- 100 105

ceived in a bearing 9 formed in an arm cast integral with the upper portion 2 of the casing of the valve, this arm extending from the shell 2 inwardly to the center of the valve and having the bearing 9 formed in its end or extending entirely across the shell 2, in which latter case the bearing 9 may be a two-part bearing, one part being secured by suitable bolts to the other. Secured on the shaft 8 is a bevel-gear 10 meshing with a bevel-pinion 11 which is keyed on the inner end of a shaft 12. This shaft extends through an opening in shell 2 forming a bearing for the shaft, and at its outer end is provided with any suitable means by which the shaft may be turned to turn the shaft 8. In Fig. 1, I have shown shaft 12 as provided with a hand-wheel 13.

Each of the movable valve-members 5 is secured to a stem 14 which projects upwardly through an opening in the pressure-plate 7. Between the pressure-plate and each of the valve-members 5 is a spiral spring 15 adapted to press the valve-member 5 against its seat. The stem 14 of each valve-member may project through its opening in the pressure-plate 7 and have an enlarged head 16 at its upper end.

If any of the valves stick there will still be one or more valve-members which will be raised, in order to furnish the necessary outlet for the steam or other gas and thus relieve the pressure. In order that the pressure at which the movable valve-members will be raised may be regulated as desired, the springs 15 for holding the valve-members upon their seats may be subjected to greater or less tension, and the means herein shown for this purpose is such that the tension of all of the springs 15 may be simultaneously adjusted. Turning the shaft 12, by means of the hand-wheel 13 moves the pressure-plate 7 toward or away from the plate 3, the pressure-plate 7 then sliding upon the posts 6. The pressure-plate 7 is formed to provide means for limiting the extent to which the springs 15 may be compressed, and for this purpose is extended at some point thereon toward the plate 3, so that it will coact with the plate 3 to arrest the movement of pressure-plate 7 toward plate 3. Thus, I have shown the central hub 17 of the pressure-plate 7, to arrest further movement of the pressure-plate when the springs 15 have been subjected to as great a tension as it is desired they should ever be subjected to. By turning the hand-wheel 13, the pressure-plate 7 may be raised and in moving thus will engage the heads 16 of the stems of the valve-members and further movement of the pressure-plate will cause the valve-members to be positively lifted from their seats.

I may provide means for steadyng the movements of the valve-members 5. This

may be readily done by the provision of a dash-pot in connection with each of the movable valve-members, and a construction employing such a dash-pot is illustrated in Fig. 3. In this figure, the pressure-plate 7 is shown as formed to provide a cylindrical chamber 18, and within this chamber is a piston 20 secured to the upper end of the stem 14. In this form of my invention, as well as in that above described, the valve-member 5 may be loosely connected to its stem 14, so that the valve will seat itself more accurately. For this purpose, I have shown the members 5 as loosely connected by a pin 22 to the stem 14.

The construction illustrated in Figs. 1, 2 and 3 and above described may be modified in numerous respects to adapt the valve for insertion at such points in a system of steam-piping as may be desired, and for greater convenience in operating the valve. Thus, in Fig. 4 I have shown the operating mechanism for the pressure-plate 7 located below the plate 3, instead of above it as in Fig. 1. For this purpose, plate 3 is formed to provide a central bearing for the shaft 8, and the bevel-gear 10 is secured to the lower end of shaft 8, this gear meshing with a pinion 11 as above described. A vertically disposed shaft 23 may be geared to the shaft 12 and have a hand-wheel on its lower end to permit of operating the pressure-plate 7 from a distance, as is shown in Fig. 5; or, as shown in Fig. 6, the wheel on shaft 12 may be a chain-wheel and a suitable chain 24 may be provided for operating this wheel and its shaft. The means for positively raising the valve-members 5 from their seats may be constructed as shown in Fig. 4, wherein the stems 25 of the valve-members 5 are rigidly secured to the pressure-plate 7 and extend loosely through the valve-members 5. These stems have heads 26 upon their lower ends, so that when pressure-plate 7 and stems 25 are raised, heads 26 will engage the valve-members 5 and lift them from their seats.

As shown in Figs. 4 and 7, the exhaust-relief-valve, as above described, may be combined with an exhaust-head, the upper portion of the casing of the valve having the form of the exhaust-head. For this purpose, the upper portion 27 of the shell may have walls 28 formed thereon for directing the steam against a plurality of teeth 29 extending inward from the shell 27.

An opening 30 may be provided in the lower portion 1 of the shell, which will carry off all of the water collecting within the casing. If desired, however, the opening for draining off the water may be above the level of plate 3 and in the upper portion of the casing of the valve, as shown at 31 in Fig. 1, and in this case a water-seal for the valve-members 5 will be provided.

In Fig. 6, I have shown the outlet from the valve as on the side of the casing. The upper portion 2 of the casing of the valve is preferably formed in two parts 32 and 33, divided vertically, as shown in Fig. 5, the shaft 12 for operating the pressure-plate 7 being mounted upon one of these parts; this construction permits of obtaining access to the interior of the valve by merely removing the part 32 of the casing, the part 33 and the operating mechanism for the pressure-plate 7 remaining in place.

Referring to Fig. 4, it will be seen that a single drainage system serves to drain both the valve-chamber and the chamber of the exhaust-head, and the construction is therefore simplified and made less expensive to manufacture.

In Fig. 8 is shown a valve of the character above set forth, having an indicator and lock for the movable pressure-member such that if it is found necessary to move this member, it can be returned to the same position and the member can be locked in any position to hold it against movement under the vibration to which the valve is usually subjected. It will be seen that the handle of the shaft 12 in Fig. 8 is affixed to a disk 40 having a plurality of holes therein arranged in a circle, and a key 41 is provided adapted to be inserted in any one of these holes and to have its threaded end enter a threaded opening in the shell of the valve. This key 41 will therefore hold the shaft 12 against movement but it can be withdrawn from the opening in the shell when it is desired to turn shaft 12. The openings in disk 40 may be numbered so that, after being moved, the shaft may be returned to and locked in the same position as that it had originally.

In Fig. 5 the upper portion of the shell is shown as made in two parts, but of course this number may be increased as desired. I have shown in Fig. 8 means for facilitating withdrawal of one or more of these parts to permit inspection and adjustment of the parts within the casing. The parts 32 and 33 of the shell are bolted together by bolts 42 and the piping 43 leading from this portion of the shell is bolted by bolts 44 to the flange 45 formed on the parts 32 and 33. I provide screws 46 passing through the flange 45 and engaging the corresponding flange on the pipe 43 so that when the bolts 44 have been loosened, the screw 46 may be turned up to raise pipe 43 slightly off of flange 45. Similarly I provide screw 47 in the coacting flanges of the parts 32 and 33, so that when the bolts 42 connecting these parts have been removed, the screws 47 may be turned up to move one section away from the other slightly. When the parts have been separated thus, the removal of one of them may be readily accomplished.

The lower portion 48 of the shell may have one or more outlet openings formed therein as shown at 49, Fig. 8, and cut-off valves may be mounted within the shell and be movable to close or open these outlets: 70 Such cut-off valves are shown at 50, the shafts thereof extending through bearings in the shell and having operating handles 51 thereon. In the structure shown, the steam enters at the bottom of the casing and leaves 75 by the outlets 49 and the upper portion of the shell above the movable valve-member 5 is connected to the exhaust. With such a structure may be combined an oil-separator built within the shell of the relief-valve, as 80 shown at 52 in Fig. 8, located between the inlet and outlet openings. The exhaust-head shown in Fig. 4 may also be combined with the structure shown in Fig. 8, as illustrated in Fig. 9, which is like Fig. 8 in all 85 respects except that the upper portion of the shell is built in accordance with Fig. 4 to combine the exhaust-head with the exhaust relief-valve.

Having now described my invention, what 90 I claim as new therein and desire to secure by Letters Patent is as follows:—

1. A valve comprising a casing, a member therein provided with a plurality of openings, a plurality of independently-movable 95 valve members, each adapted to close one of said openings, a spring for each of said valve-members arranged to hold the same upon its seat, and means for regulating the tension of all of said springs simultaneously, 100 substantially as set forth.

2. A valve comprising a casing, a member therein provided with a plurality of openings, a plurality of independently-movable valve-members, each adapted to close one of said openings, a spring for actuating each of said valve-members, a pressure-member engaging all of said springs, and means operated from outside the casing for moving said pressure-member to regulate the tension of 110 all of said springs, substantially as set forth.

3. A valve comprising a casing, a member therein provided with a plurality of openings, a plurality of independently-movable valve-members, each adapted to close one of 115 said openings, a spring for each of said valve-members arranged to hold the same upon its seat, means for regulating the tension of all of said springs simultaneously, and means for positively raising said valve-members from their seats, substantially as set forth.

4. A valve comprising a casing, a member therein provided with a plurality of openings, a plurality of independently-movable 125 valve-members, each adapted to close one of said openings, a spring for actuating each of said valve-members, a pressure-member engaging all of said springs, and means operated from outside the casing for moving said 130

- pressure-member and thereby raising said valve-members from their seats, substantially as set forth.
5. A valve comprising a casing, a member therein provided with a plurality of openings, a plurality of independently-movable valve-members, each adapted to close one of said openings, a spring for each of said valve-members arranged to hold the same upon its seat, means for regulating the tension of all of said springs simultaneously, and means for limiting the extent to which said springs may be compressed by said regulating means, substantially as set forth.
- 15 6. A valve comprising a casing, a member therein provided with a plurality of openings, a plurality of independently-movable valve-members, each adapted to close one of said openings, a spring for actuating each of said valve-members, a pressure-member engaging all of said springs, means operated from outside the casing for moving said pressure-member and thereby raising said valve-members from their seats, and means for limiting the movement of said pressure-member, substantially as set forth.
- 20 7. A valve comprising a casing, a member therein provided with a plurality of openings, a plurality of independently-movable valve-members, each adapted to close one of said openings, a dash-pot for each of said valve-members adapted to regulate the movement thereof, a spring for each of said valve-members arranged to hold the same upon its seat, and means for adjusting the tension of all of said springs simultaneously, substantially as set forth.
- 25 8. A valve comprising a casing consisting of two parts secured together, a plate formed integral with one of said parts and provided with a plurality of openings, a movable valve-member for closing each of said openings, a spring for actuating each of said valve-members, a pressure-member engaging said springs, posts on said plate on which said pressure-member is movable, a shaft having a bearing in said plate, coacting threads on said shaft and pressure-member, and means operated from outside the casing for rotating said shaft, substantially as set forth.
- 30 9. The combination of a tubular member having a plate extending across the same and provided with a plurality of openings, an exhaust head secured to said member, a plurality of independently-movable valve-members each normally closing one of said openings, a spring actuating each of said valve-members, a pressure-member engaging each of said springs, a shaft having a bearing in said plate, coacting threads on said pressure-member and shaft, and means for rotating said shaft, substantially as set forth.
- 35 10. The combination of a tubular member having a plate extending across the same and

provided with a plurality of openings, a two-part shell secured upon said member, said parts being removable therefrom and from each other, a plurality of independently-movable valve-members each normally closing one of said openings, a spring actuating each of said valve-members, a pressure-member engaging all of said springs, a shaft mounted for rotation upon one of the parts of said shell, means for rotating said shaft, and means actuated by said shaft for moving said pressure-member, substantially as set forth.

11. The combination of a tubular member having a plate extending across the same and provided with a plurality of openings, a shell secured to said member and removable therefrom to permit access to said plate and the parts coacting therewith, a plurality of valve-members each normally closing one of said openings, a spring actuating each of said valve-members, a pressure-member for regulating the tension of all of said springs, a shaft, means for rotating the same, and means actuated by said shaft for moving said pressure-member, substantially as set forth.

12. The combination of a shell having inlet and outlet openings, a plate within the shell extending across the same and having a plurality of openings therein, a plurality of valve-members each normally closing one of said openings, a spring actuating each of said valve-members, a pressure-member, a shaft journaled in a bearing in said shell and a connection between said shaft and said pressure-member for moving the latter to vary the tension of all of said springs, a portion of said shell being removable independently of said shaft and connection to permit access to said valve-members, substantially as set forth.

13. The combination of a shell having a steam inlet, a steam outlet and an exhaust outlet, a cut-off valve for said steam outlet mounted within the shell, means for operating said valve from outside the shell, a plate extending across said shell between the steam outlet and the exhaust outlet and having a plurality of openings therein, a valve-member for each opening, a spring for each valve-member, and means for simultaneously regulating the tension of all of said springs, substantially as set forth.

14. A valve comprising a casing, a member mounted therein provided with a plurality of openings, a plurality of independently moving valve-members each adapted to close one of said openings, a spring for each of said valve-members arranged to hold the same upon its seat, means for regulating the tension of all of said springs simultaneously, and a lock for said regulating means, substantially as set forth.

15. A valve comprising a casing, a mem-

ber therein provided with a plurality of openings, a plurality of independently movable valve-members each adapted to close one of said openings, a spring for each of said valve-members arranged to hold the same upon its seat, and an indicator coacting with said regulating means to indicate the position thereof, substantially as set forth.

16. A valve comprising a casing, a member therein provided with a plurality of openings, a plurality of independently movable valve-members each adapted to close one of said openings, a spring for each of said valve-members arranged to hold the

same upon its seat, a pressure-member engaging all of said springs, a shaft extending through the casing and connected to said pressure-member for moving the same to regulate the tension of all of said springs, 20 means for operating said shaft, a lock for holding said shaft against movement, and means for indicating the position of said shaft, substantially as set forth.

This specification signed and witnessed 25
this 28th day of April, 1909.
